CLAIM

The ornamental design for a display panel with icon, as shown and described.

DESCRIPTION

FIG. 1 is a front view of a display panel with icon, showing my new design; and,

FIG. 2 is an enlarged view of the icon of FIG. 1, shown separately for completeness of illustration.

The broken lines at the perimeter of the figure illustrates the display panel, and the remaining broken lines illustrate portions of the icon elements. None of the broken lines form part of the claimed design.
